UNITED STATES PATENT OFFICE

121,520

DESIGN FOR A PIPETTE

James J. Moran, Vineland, N. J., assignor to Kimble Glass Company, Vineland, N. J., a corporation of Illinois

Application April 5, 1939, Serial No. 84,075

Term of patent 14 years

To all whom it may concern:

Be it known that I, James J. Moran, a citizen of the United States of America, residing at Vineland, in the county of Cumberland and State of New Jersey, have invented a new, original, and ornamental Design for a Pipette, of which the following is a specification, reference being had thereto the accompanying drawing, forming a part thereof, in which

Fig. 1 is a side elevational view of a pipette showing the new design;

Fig. 2 is a front view of the pipette; and
Fig. 3 is a top view thereof.

The dominant feature of the design resides in the specific arrangement of the arrows on the side face of the pipette shown in alignment with the principal division lines of the scale on the front face thereof in the relation illustrated.

I claim:

The ornamental design for a pipette, substantially as shown and described.

JAMES J. MORAN.
